Attorney.

UNITED STATES PATENT OFFICE.

LESLIE STUART CAMPBELL, OF BRIGHTON, ENGLAND.

CARBURETER.

1,393,426.

Specification of Letters Patent. Patented Oct. 11, 1921.

Application filed September 20, 1920. Serial No. 411,588.

(GRANTED UNDER THE PROVISIONS OF THE ACT OF MARCH 3, 1921, 41 STAT. L., 1818.)

To all whom it may concern:

Be it known that I, LESLIE STUART CAMPBELL, a subject of the King of Great Britain and Ireland, residing at Brighton, in the county of Sussex, England, have invented a new and useful Improvement in Carbureters for Internal-Combustion Engines, (for which I have filed application in England June 11, 1919, Patent #154,951,) of which 10 the following is a specification.

This invention relates to carbureters for internal combustion engines of the type in which the liquid fuel is allowed to flow over a surface of absorbent material over which 15 the air induced by the suction of the engine passes and it has for its object to obtain a maximum efficiency of the engine with a minimum consumption of fuel. A further object of this invention is to obtain simplicity of construction and therefore economy in manufacture. Another object is to avoid the presence of water in the fuel from interfering with the action of the carbureter. A still further object of this invention is to 20 obtain a positive control of the supply of fuel and therefore of the speed of the engine and consequently of the speed of the vehicle driven by same.

I attain these ends by the construction 30 shown in the accompanying drawings in which:—

Figure 1 is a view in sectional elevation of a convenient embodiment of this invention.

Fig. 2 is a sectional view thereof on line 35 $v v$ Fig. 1 and

Figs. 3 and 4 are views in elevation and plan partly in section showing an alternative construction.

Throughout the views similar parts are 40 marked with like letters of reference.

Within a cylindrical chamber a is a cylindrical frame b —of a smaller diameter than the chamber a —on the exterior of which is a jacket of suitable absorbent material b' . 45 On the upper part c of this frame is a distributing chamber d in the vertical wall of which are a series of minute holes or ports through which the fuel in said auxiliary chamber passes on to the absorbent jacket b' . 50 Leading into the distributing chamber d is a pipe f which is connected to a fitment h attached to the side of the chamber a . On this fitment is a pipe h' leading to the fuel

supply and in said fitment is a needle valve m for controlling the supply of fuel passing 55 into the distributing chamber d . A second valve h^2 may be fitted to the pipe h' to limit the maximum supply of the liquid fuel. In the bottom of the chamber a are one or more orifices n for the admission of air to said 60 chamber. On the interior face of the chamber a are arranged one or more baffle plates p arranged so as to direct the flow of air over the surface of the jacket b' the preferred form being that of a helix as shown 65 in Fig. 1.

In the upper part a' of the chamber a which is of a reduced diameter is located the main throttle valve x . The needle valve m is coupled with said throttle valve by means 70 of a crank pin m' carried by the valve m which engages a slot in the controlling lever x^2 of said throttle valve.

The action of the carbureter is as follows:—The liquid fuel flows by gravity into 75 the distributing chamber d and out of said chamber through the small holes or ports e on to the absorbent jacket b' . The air drawn in through the inlets n by the suction of the engine picks up the liquid fuel from the 80 absorbent jacket and forms the explosive mixture.

If desired the carbureter may be provided in the upper part of the chamber a with auxiliary air inlets n' controlled by sliding 85 shields n^2 carried by a ring n^2 mounted to slide on the upper part a' of the chamber a said ring being coupled to the throttle valve x' by means of an arm n^4 mounted on the spindle of said valve and engaging a slotted 90 recess n^5 formed in the ring n^2 , as shown in Figs. 3 and 4.

The frame b may be made of any suitable construction and form, that shown, which consists of a cylinder, being a suitable 95 and convenient one.

What I claim is:—

1. A carbureter for internal combustion engines comprising a chamber the upper part of which is adapted to be put in communication with the induction pipe of the engine, an air inlet in the bottom of said chamber, a frame located within said chamber, a distributing chamber mounted on the top of said frame, an absorbent jacket on 100 the exterior of said frame the exterior diam- 105

- eter of the jacketed frame being less than the internal diameter of the main chamber, means of communication between said distributing chamber and said absorbent jacket, 5 a port in said distributing chamber which is in communication with the liquid fuel supply, and means for controlling the amount of liquid fuel passing into said distributing chamber.
- 10 2. A carbureter for internal combustion engines comprising a chamber the upper part of which is adapted to be put in communication with the induction pipe of the engine, an air inlet in said lower part of said chamber, a frame located within said chamber, a distributing chamber mounted on the top of said frame, an absorbent jacket on the exterior of said frame the exterior diameter of said jacketed frame being less than the internal diameter of the main chamber, baffle plates on the inner wall of the main chamber, a series of small holes or ports in the vertical wall of said distributing chamber, a port in said distributing chamber which is 15 in communication with the liquid fuel supply, and means for controlling the amount of liquid fuel passing into said chamber.
3. In a carbureter for internal combustion engines the combination of a chamber the upper part of which is adapted to be put in communication with the induction pipe of the engine, air inlets in the lower part of said chamber, a frame located within said chamber, a distributing chamber mounted on the top of said frame, an absorbent jacket on the exterior of said frame and said distributing chamber, auxiliary air inlets in the upper part of the main chamber above the distributing chamber, means for controlling 20 said auxiliary inlets, means of communication between the distributing chamber and the absorbent jacket, a port in said distributing chamber which is in communication with the liquid fuel supply, and means for regulating the amount of liquid fuel passing through said port.
- 25 latting the amount of liquid fuel passing into 45 said chamber.
4. In a carbureter for internal combustion engines the combination of a chamber the upper part of which is adapted to be put in communication with the induction pipe 50 of the engine, one or more air inlets in the lower part of said chamber, a frame located within said chamber, a distributing chamber located on the top of said frame, a plurality of small holes or ports in the vertical 55 wall of said distributing chamber, an absorbent jacket on the exterior of said frame, helically arranged baffle plates on the inner wall of the main chamber, auxiliary air inlets in the main chamber above the distributing chamber, means for controlling said auxiliary inlets, a port in the distributing chamber which is in communication with the liquid fuel supply, and a valve for varying the area of said port. 60
5. In a carbureter for internal combustion engines, the combination of a cylindrical chamber the upper part of which is adapted to be put in communication with the induction pipe of the engine, an air inlet 70 in the lower part of said chamber, a frame centrally located within said chamber, an absorbent jacket mounted over said frame, a cylindrical distributing chamber located on the top of said frame said frame and said 75 distributing chamber being of a smaller diameter than the main chamber, baffle plates in the main chamber located between the inner face of the wall of said chamber and the outer face of the absorbent jacket, ports in 80 said distributing chamber communicating with said jacket, a port in said chamber which is in communication with the liquid fuel supply, and means for regulating the amount of liquid fuel passing through said 85 port.

LESLIE STUART CAMPBELL.
